US00D357033S

United States Patent [19]

Kenney

[11] Patent Number: Des. 357,033

[45] Date of Patent: * Apr. 4, 1995

[54] PAWL AND RATCHET FOR ALIGNING
CONTINUOUS FEED PAPER IN A PRINTER
AND EMBOSSE

[75] Inventor: **Raymond W. Kenney**, Tulsa, Okla.

[73] Assignee: **Sandco, Inc.**, Tulsa, Okla.

[*] Notice: The portion of the term of this patent
subsequent to May 24, 2008 has been
disclaimed.

[**] Term: **14 Years**

[21] Appl. No.: **905,844**

[22] Filed: **Mar. 26, 1992**

[52] U.S. Cl. **D18/56**

[58] Field of Search 400/641, 202; 346/1.1,
346/136; D18/56; 101/232, 228
